UNITED STATES PATENT OFFICE.

ANDREW DE VRIES, OF SOUTH BEND, INDIANA, ASSIGNOR TO WESTINGHOUSE ELECTRIC & MANUFACTURING COMPANY, A CORPORATION OF PENNSYLVANIA.

DESIGN FOR A SPREADER ARM FOR TRANSMISSION WIRES.

Application filed January 14, 1927. Serial No. 20,370. Term of patent 3½ years.

To all whom it may concern:

Be it known that I, ANDREW DE VRIES, a citizen of the United States, residing at South Bend, in the county of St. Joseph and State of Indiana, have invented a new, original, and ornamental Design for a Spreader Arm for Transmission Wires, of which the following is a specification, reference being had to the accompanying drawing, constituting a part hereof.

The figure is an elevational view of my

new design for a spreader arm for transmission wires, the dotted line portions being shown for the purpose of disclosing the manner in which the spreader arm is used.

I claim:

The ornamental design for a spreader arm for transmission wires, as shown.

In testimony whereof, I have hereunto subscribed my name this 6th day of January, 1927.

ANDREW DE VRIES.
